UNITED STATES PATENT OFFICE.

WILLIAM F. MALONEY, OF CHICAGO, ILLINOIS.

CALENDAR.

SPECIFICATION forming part of Letters Patent No. 629,864, dated August 1, 1899.

Application filed December 2, 1898. Serial No. 698,091. (No model.)

To all whom it may concern:

Be it known that I, WILLIAM F. MALONEY, a citizen of the United States, residing at Chicago, in the county of Cook and State of Illinois, have invented certain new and useful Improvements in Calendars, of which the following is a specification.

My invention relates to certain new and useful improvements in calendars, and particularly to that class commonly used as desk-calendars and comprising a number of sheets arranged in a pad upon a suitable base and each sheet bearing calendar information relative to a day of the year and a memorandum-space.

The object of the invention is to provide for hanging the used sheets of a calendar-pad in an upright vertical position behind the unused sheets, so that the calendar will take up but very little desk-space and all the sheets of the pad be preserved on file in a neat condition as long as desired.

Another object is to display the calendar information relative to the current day in a conspicuous manner and at the same time provide a large memorandum-space on each sheet, the file of used sheets being hung in regular order, with the last sheet at the back, so that they can be readily consulted at any time.

A further object is to provide a device for holding or retaining the pad on a suitable base and embodying also a hanger to receive the used sheets at the end of each day, the combined holder and hanger being joined together, so that the sheets may pass freely and easily from the holder to the hanger and be restrained from displacement at all times; and further objects of the invention are to provide a top sheet for the calendar-pad bearing a yearly calendar, a picture, a photograph, an advertisement, or other matter, which will remain in plain view at the front of the hanging used sheets at all times throughout the year, and a prominent figure designating a day of the month on each sheet, with the name of the month above it, and on one side a miniature calendar of the entire preceding month and on the other side a miniature calendar of the next succeeding month.

My invention also has other objects in view, which will appear more fully hereinafter.

With these and other objects in view the invention consists of the peculiar construction and arrangement of parts hereinafter described in connection with the accompanying drawings, in which—

Figure 1 is a perspective view of my improved calendar, and Fig. 2 is a sectional view.

Referring to the drawings, in which like letters of reference denote corresponding parts in both of the figures, A designates a base for the calendar-pad B, and it is made lower at the front than at the back, preferably, so that the current sheet will be in the best position to display the information it bears and also bring the blank memorandum-space into the most convenient position for use, as illustrated in the drawings.

The calendar-pad may be of the usual form, having a separate sheet for each day of the year properly printed, each sheet bearing, near its top preferably, the name of the month and beneath it a figure, in prominent type, designating one day of the month, a miniature calendar D of the preceding month at the left, and a miniature calendar E of the next succeeding month at the right, of the figure. At the bottom of the sheet I may print the day of the week, followed by the date, as indicated, together with such other information as may be desirable, the arrangement of the printed matter on the sheet being, preferably, such as to provide a large memorandum-space C.

The first sheet F of the pad may bear a yearly calendar, as shown in the drawings, and this sheet and the used sheets of past days are hung in such a manner that the first sheet will always be in plain view throughout the life of the calendar. These used sheets are generally carried forward as far as possible to the front of the hanger; but they may be pushed back to the rear of the hanger at any time for the purpose of consulting the entire first sheet or any of the used sheets where such action becomes necessary. The first sheet F may bear a picture, a photograph, an advertisement, or any other information desired.

A device for holding and hanging the sheets is removably connected to the base in a suitable manner, and it passes through perforations in the pad at G for the purpose of retaining the sheets permanently in place either on the base or on the hanger. This combined holder and hanger device is preferably made of a continuous piece of wire, and its ends are fastened to the base, while the looped portion is carried rearward and then bent or doubled back under until the straight piece H, which connects the two members of the device and constitutes the front of the hanger, is brought close to the uprights I. The doubled-under part constitutes the hanger J, the members of which are substantially parallel with the horizontal rearward extensions K, although this particular arrangement and relation of these parts is not absolutely essential. It will thus be observed that the upright parts I of the wire constitute the holder for retaining the pad on the base and the doubled-under part J is the hanger for the used sheets, these parts being connected by the horizontal parts or extensions K.

The hanger is elevated sufficiently to permit the used sheets to hang free from the desk on which the calendar stands, and the front of the hanger H is located close to the uprights I, but without interfering with the transfer of the sheets from the pad to the hanger as it is used each day. The hanger is large enough to accommodate the entire pad, and the arrangement is such that the used sheets will be retained on file in regular order and good condition until all the sheets have been transferred, and then the used pad may be replaced by a new pad and the old pad laid aside or destroyed.

The hanging used sheets of the pad occupy but little room, and the calendar therefore takes up only a small area of desk-space, and it is obvious that the calendar can be moved about at pleasure without in any way disarranging the sheets or mixing up the used and the unused sheets, these being maintained separate and distinct from each other at all times. When a sheet has been used, it is carried up on the uprights and back over the extensions and into its place on the hanger, where it is held in alignment with the other used sheets as long as desired.

The arrangement of the numeral designating the day of the month and miniature calendars of the preceding and succeeding months on each sheet is of great convenience for reference, and the yearly calendar, which may be printed on the first sheet F, is always in plain view; but it will be understood that I do not restrict myself in any way to a calendar-pad printed in any particular manner, although I have found the arrangement and character of the printed information as herein described to be of especial value and convenience. The construction of the base A may also be varied—for example, the top thereof

may be horizontal, so that the pad will lie flat instead of inclined, as shown, and the combined holder and hanger device may be made of two pieces of wire instead of one, the upper ends being bent to form a front substantially like the front H illustrated to prevent the used sheets from becoming disarranged.

The lower ends of the holder are passed through openings in the base and provided with thumb-nuts L, so that the holder and hanger device can be removed from the base and a new calendar arranged in position at any time.

Having thus fully described my invention, what I claim as new, and desire to secure by Letters Patent, is—

1. The combination with a base for supporting a calendar-pad, of a holder to retain the pad in place on the base, and a hanger to receive the used sheets from the pad and support them in a hanging vertical position behind the unused sheets of the pad, substantially as described.

2. The combination with a base for supporting a calendar-pad, of a holder to retain the pad in place on the base, and a hanger arranged above and behind the pad to receive the used sheets from the pad and support them in a vertical swinging position behind the pad, substantially as described.

3. The combination with a base for supporting a calendar-pad, of a combined holder and hanger device connected to the base and adapted to hold the unused sheets of the pad in a substantially flat position on the base and support the used sheets in a substantially vertical swinging position behind the unused sheets, substantially as described.

4. The combination with a base for supporting a calendar-pad, of a combined holder and hanger made of a single piece of wire having its ends removably connected to the base and adapted to hold the unused sheets of the pad in a substantially flat position on the base and support the used sheets of the pad in a substantially vertical swinging position behind the unused sheets, substantially as described.

5. The combination with a base for supporting a calendar-pad, of a combined holder and hanger device comprising uprights leading from the base, horizontal connecting parts, and a doubled-under part constituting a hanger for the used sheets of the pad, substantially as described.

6. The combination with a base for supporting a calendar-pad, of a combined holder and hanger device made of a single piece of wire having its ends removably connected to the base and comprising uprights leading from the base and constituting the holder, a hanger located in rear of the holder, and substantially horizontal connecting parts above the hanger and joining the holder and the hanger together, substantially as described.

7. The combination with a base for support-

ing a calendar-pad, of a combined holder and hanger device made of a single piece of wire removably connected to the base and comprising parallel uprights constituting the holder, horizontal rearward extensions from the upper ends of the uprights, and a hanger formed by doubling the looped end of the wire

under the horizontal extensions, substantially as described.
